UNITED STATES PATENT OFFICE

2,629,203

MOVING FIGURE WHEELED TOY

Hurley Leon Brown, Kokomo, Ind.

Application April 14, 1950, Serial No. 155,850

2 Claims. (Cl. 46—104)

1

This invention relates to certain new and useful improvements in moving figure wheeled toy and more particularly to a power-driven toy formed to simulate a duck, having a head portion provided with a movable jaw and eyes which are intermittently illuminated.

The invention has for a principal object the provision of means for moving the movable jaw and intermittently illuminating the eyes as the toy is propelled by power over a surface.

A still further and equally important object of this invention is to provide a toy of this character comprising an arrangement of parts which will afford ready assembly and economical manufacture.

Ancillary to the principal object of this invention is to provide a toy which will afford the maximum amusement to a child.

Other objects will appear hereinafter.

The invention consists in the novel combination and arrangement of parts to be hereinafter described and claimed.

The invention will be best understood by reference to the accompanying drawings showing the preferred form of construction, and in which:

Figure 1 is a perspective view of the toy embodying my invention;

Fig. 2 is a face elevational view of the same;

Fig. 3 is a sectional detail view taken substantially on line 3—3 of Fig. 5;

Fig. 4 is a fragmentary elevational view taken substantially on line 4—4 of Fig. 5; and

Fig. 5 is a sectional detail view taken substantially on line 5—5 of Fig. 3.

The several objects of the invention are accomplished by the preferred form of construction shown in the accompanying drawings and in which 10 indicates a body formed to simulate a living creature, such for example, a duck, having a head portion 11 from which extends an integral upper jaw 12.

A lower jaw is indicated at 13 and is hinged to the body by means of a hinge 14. The body comprises two sections 15 and 16 connected together by suitable adhesive material or the like.

The head 11 provides a transverse opening 17 closed by suitable plastic or glass disks 18 painted or otherwise impressed to simulate eyes.

The head 11 further includes a transverse opening 19 in parallel relation with respect to the opening 17 and into which the sockets 20 supporting electric bulbs 21 within the opening 17 project. The electric bulbs 21 are disposed adjacent the eye simulating disks 18 and are adapted in a manner hereinafter described to be intermittently illuminated.

2

The main portion of the body 10 provides a compartment 22. In this compartment 22 is arranged a spring motor 23 of any approved construction including a power spring 24 and a train of gears 25 which acts as a governor to drive a driving gear 26. This driving gear 26 drives a pinion which is mounted on a shaft 27 extending transversely of the body and having eccentrically mounted on its opposite end portion, wheels 28.

The spring motor has a winding key 29 by which the spring 24 of the motor may be placed under driving operation.

The tail portion 30 of the body 10 carries a wheel 31 mounted on a suitable shaft 32 in turn carried by the body 10.

The arrangement is such that when the simulated duck is propelled over a surface by the motor 23 the body of the duck will pivot about the shaft 32 to simulate waddling.

In the tail portion 30 of the body 10 is a compartment 33 into which I mount a dry cell battery 34. This battery 34 is connected by circuit wires 35 with the electric bulbs 21. Interposed in this circuit connection is a switch 36 normally in open condition. The switch is supported on a block 37 extending transversely of the body 10.

On the shaft 27 is eccentrically mounted a disk 38. This disk 38 intermittently engages an element 39 of the switch 36 to intermittently close the same and intermittently energize the electric bulbs 21. This same disk 38 is also employed to clamp the movable jaw 13 against the stationary jaw 12. This is accomplished by providing in the disk 38 a groove 40. Mounted in this groove 40 is a loop 41 of a pull cord 42.

The cord 42 extends around a fixed pin 43 carried by the body 10. The opposite or upper end portion of this pull cord 42 extends through an eye 44 of a bolt 44 connected to the movable jaw 13 as shown in Fig. 4. Such end portion of the pull cord 42 is fixed to the body 10 as at 45, Fig. 5. The arrangement is such that when the disk 38 is in the position shown in Fig. 4, the cord 42 is pulled tight, clamping the movable jaw 13 against the stationary jaw 12. When in the position shown in Fig. 3, the pull cord 42 allows the jaw 13 to pivot to an open position as shown in Fig. 3.

By this arrangement I have provided a single means for effecting closing of the switch 36 and for moving the jaw 13. Each time that the switch 36 is closed, the electric bulbs will be illuminated to simulate winking of the eyes.

A toy constructed in accordance with the foregoing description is simple in construction. The

simulated walking of the toy, the simulated winking of the eyes, and the opening and closing of the mouth, will afford great amusement to a child.

The toy may be assembled quickly and comprises relatively few parts, thereby affording economical manufacture.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having thus described my invention, what I claim as new and desire to protect by Letters Patent is:

1. A toy comprising a body, a shaft extending transversely of the body, supporting wheels eccentrically mounted on the shaft, a power unit within the body and having driving connection with the shaft, said body comprising a head, said head having a transverse opening formed therein, eye simulating disks mounted in said head at opposite ends of said opening, electric bulbs mounted in said opening adjacent said disks, a power circuit for said bulbs including a switch, and a disk eccentrically mounted on said shaft and engaging an element of said switch for intermittently closing said switch, said head including a stationary and a movable jaw, and means operable by the eccentrically mounted disk and connected to the movable jaw for moving said jaw relative to said stationary jaw intermittently with the closing of said switch, said last-named means including a pull cord within said body and having connection with said movable jaw and having a

loop mounted in a groove of said eccentrically mounted disk.

2. A toy comprising a body providing a hollowed out portion, a head having a passage extending downwardly therefrom and having communication with said hollowed out portion of said body, said head including a movable jaw and a stationary jaw, a shaft extending transversely of the body, supporting wheels eccentrically mounted on said shaft, a motor mounted in said hollowed out portion of said body and having driving connection with the shaft, a pull cord extending through said passage for connection to said movable jaw, a disk eccentrically mounted on said shaft and having a groove formed in its periphery, said pull cord having a loop extending around said disk within said groove and passing upwardly through said passage to said movable jaw, said head having a pair of simulated eyes, means within said head for intermittently illuminating said eyes, said means having a power circuit and said circuit including a switch, said circuit and said switch having connection through said passage with said eye illuminating means, an element of said switch adapted to be intermittently engaged by said eccentrically mounted disk to complete a circuit to illuminate said eyes.
